DESIGN FOR A PROJECTOR

Samuel Marcus, New York, and Evan J. Anton,
Sunnyside, N. Y.

Application December 19, 1945, Serial No. 124,878

Term of patent 14 years

(Cl. D61—1)

To all whom it may concern:

Be it known that we, Samuel Marcus and Evan J. Anton, citizens of the United States, residing, respectively, at New York, in the county and State of New York, and Sunnyside, county of Queens and State of New York, have invented a new, original, and ornamental Design for Projectors, of which the following is a specification, reference being had to the accompanying drawing, forming part thereof, in which—

Fig. 1 is a top plan view of a projector, showing our new design;

Fig. 2 is a side view thereof;

Fig. 3 is a rear view thereof; and

Fig. 4 is a front view thereof.

We claim:

The ornamental design for a projector, as shown.

SAMUEL MARCUS.
EVAN J. ANTON.
